UNITED STATES PATENT OFFICE.

JOHN W. LESLIE, OF EVANSTON, ILLINOIS.

JOINT.

Application filed October 25, 1920. Serial No. 419,447.

To all whom it may concern:

Be it known that I, JOHN W. LESLIE, a citizen of the United States, and a resident of Evanston, in the county of Cook and State of Illinois, have invented certain new and useful Improvements in Joints, of which the following is a specification:

This invention relates to tension resisting joints particularly useful in the application of tensional metallic binders to boxes and packages. It is an object of the invention to provide a joint of the character described, simple and economical in construction, easy in application, and efficient in operation.

In the drawings which represent an illustrative embodiment of the invention:

Fig. 1 is a perspective view of a connecting member forming an element of the joint; Fig. 2 is a perspective view of the joint embodying my invention; and

Fig. 3 is a cross sectional view on the line 3—3 of Fig. 2.

The joint shown in the drawing is applied upon flat metallic tensional box strappping. The most efficient types of joints heretofore in use for such box strapping have comprised the assembly of these box strap ends superposed upon each other and enclosed in a reinforcing girth, the whole being simultaneously deformed or crimped to produce conjoint interlocking tension resisting deformations. The joint shown in the drawings is of the same general type, but provides a means whereby the conjoint interlocking deformations need be made only in one box strap end and the reinforcing girth, instead of in two box strap ends and the girth as has been the practice heretofore. As is well known, joints in metallic binders, are customarily made with small hand tools. Where the box strapping is heavy and stiff, the formation of the joint involving a substantial distortion of a double thickness of the binder and the reinforcing girth as well by means of a hand tool calls for considerable effort, and there is distinct limitation upon the thickness of binders which can efficiently be joined at their ends with hand tools under methods of the prior art.

Thus the invention reduces the effort necessary to make a joint and correspondingly increases the range of the box strapping or similar tensional binders which may be em-

ployed by joining their ends with hand tools.

In the drawings, I provide a compound or double reinforcing girth comprising two oppositely directed extensions 1 and 2, each having wings 3, folded under so that each forms a sleeve, adapted to receive the end of a box strap. The two extensions 1 and 2 are connected by the integral enlargement 4. This enlargement surrounds a central aperture 5 of a size to permit the protrusion therethrough of a box strap end threaded through the sleeve 1.

As shown in the drawings, the two sides of the aperture 5 are offset vertically. Thus the edge 6, adjacent the extension 2 is deflected downwardly a little below the plane of the top of the extension 2. The opposite edge 7 of the aperture 5 is raised substantially above the edge 6, the whole extension 1 being elevated above the plane of the extension 2 as indicated at 8.

Referring now to Fig. 2, which shows the finished joint, two box strap ends 9 and 10, oppositely extending, are threaded in opposite directions between the two sleeves formed by the extensions 1 and 2. Since these extensions are on different levels and each encloses a box strap end and guides the same, these box strap ends mutually forced forward will travel toward each other on different levels. The box strap end 9 encountering the depressed edge 6 at the aperture will be deflected slightly downwardly while the box strap end 10 progressing through the extension 1 will clear the box strap end 9 and pass through the aperture 5. Thus in this construction, the box strap ends may be forced in opposite directions indefinitely without interfering with each other, as would be the case if they were fed in opposite directions through an uninterrupted sleeve element.

Each box strap end being thus threaded through one of the sleeves formed by the extensions 1 and 2 and the box strap ends being tightened around the box or package, tension resisting joints 11 and 12 are formed between and involving the extensions 1 and 2 and the enclosed box strap ends. These joints are shown for illustrative purposes as of the type disclosed in Flora Patent 1,252,680. Obviously other types of joints involving a reinforcing girth or element and a box strap end might also be used.

2
By this construction the conjoint interlocking deformations involved in the joint are formed in one thickness of a box strap and the reinforcing girth, instead of in two thicknesses of box strap and the girth, as is the case in the prior art construction, with the reduction in the effort necessary to manipulate hand tools and the corresponding increase in the range of thickness of the 10 binder employed, previously referred to.

The joint is particularly useful in connection with baling or the like, wherein the package to be supplied with a binder is compressed when the binder is applied. In such 15 use the connecting element shown in Fig. 1 can be applied upon one end of a tie or binder, as for instance the end 9, this assembly and the joint 11 being made prior to the application of the binder. Thereafter 20 the binder can be applied about the package under compression, the end 10 threaded through the extension 1 protruding through the aperture 5, the binder drawn taut, and the joint 12 formed, after which so much of 25 the binder as protrudes through the aperture 5 may be cut off as close as desired.

Having described my invention, I claim:

1. A joint in tension resisting metallic binders for boxes, packages or the like, comprising 30 a girth having a channel member arranged to receive a binder end, and an associated channel member arranged to receive an oppositely extending binder end, the entrance ends of said channel members being 35 located at the ends of the girth and the exit ends thereof being located intermediate the ends of the girth, said latter ends being offset to guide the binder ends as they are fed into overlapping position with respect to 40 each other so as to prevent interference between the two ends.

2. A joint for metallic tension resisting binders for boxes or packages, comprising in combination a pair of oppositely extended 45 binder ends, and a connecting member for said ends, said connecting member being provided with a pair of sleeve-like members arranged in different planes and each adapted to receive only a single thickness 50 of binder end, each of said sleeve-like members and its single binder end having deformations impressed therein edgewise of the sleeve-like member and binder end.

3. A connecting element for forming a 55 joint in box strap ends or the like comprising a pair of oppositely extending members, each adapted to be secured individually to a box strap end, and to guide the same as it is fed longitudinally therein, and means 60 in the connecting element, for deflecting said binder ends relatively to permit the same to clear each other as they are fed into overlapping position.

4. A joint for flat metallic tensional box 65 strapping, comprising in combination a pair

of oppositely extending box strap ends, a connecting member separately secured to each thereof by a tension resisting joint, said connecting member comprising strap end guideways located in different parallel 70 planes, and being provided with a slot at the end of one of said guideways.

5. A tension resisting joint comprising a pair of oppositely directed box strap ends, a unitary connecting member therefor, said connecting member comprising a central portion and a pair of extensions each adapted to enclose one of the strap ends, each of 75 said extensions being secured to the strap end embraced thereby by conjoint interlocking deformations formed in the extension and the strap end embraced thereby, said central portion being provided with a transversely extending slot arranged substantially in alignment with one of said extensions.

6. A tension resisting joint for box strapping comprising a pair of oppositely directed box strap ends and a connecting member, said connecting member comprising a portion adapted to be secured to each 80 box strap end separately, and a central enlargement having an aperture therein adapted to permit protrusion of a box strap end.

7. A tension resisting joint for box strapping comprising a pair of oppositely directed box strap ends and a connecting member, said connecting member comprising oppositely extending portions, each of 85 which is adapted to embrace one of the box strap ends, said connecting member comprising a central enlargement having an aperture therein.

8. A tension resisting joint for box strapping comprising a pair of oppositely directed box strap ends and a connecting member, said connecting member comprising a pair of oppositely extending sleeves and an enlarged central portion, provided 100 with a transversely extending slot adapted 105 to permit the passage therethrough of one of said strap ends.

9. As an article of manufacture, a connecting member for box strap ends comprising a pair of oppositely directed extensions 110 adapted to form enclosing sleeves for box strap ends, a central enlargement provided with an aperture, adapted to permit the passage therethrough of one of the strap ends.

10. As an article of manufacture, a connecting member for box strap ends comprising a pair of oppositely directed extensions adapted to form enclosing sleeves for box strap ends, a central enlargement provided 115 with an aperture, the sides of said aperture being offset so as to permit box strap ends being fed in opposite directions along extensions to pass each other and one thereof to protrude through the aperture.

11. As an article of manufacture, a con-

necting device for box strap ends, comprising a pair of oppositely extended portions adapted to be secured upon box strap ends, and a central enlargement having an aperture therein, one side of said aperture being deflected relatively downwardly, the other relatively upwardly.

5 12. As an article of manufacture, a connecting device for box strap ends, comprising a pair of oppositely extended portions adapted to be secured upon box strap ends,

and a central enlargement having an aperture therein, the portion of the device including one side of the aperture and extending therefrom to the adjacent end of the device being raised above the level of the remainder thereof.

15 In witness whereof, I hereunto subscribe my name this 23rd day of September, A. D., 1920.

JOHN W. LESLIE.
